UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

TOY SUBMARINE.

1,351,565.

Specification of Letters Patent. Patented Aug. 31, 1920.

Application filed May 13, 1918. Serial No. 234,200.

To all whom it may concern:

Be it known that I, ALFRED C. GILBERT, a citizen of the United States, residing in the city and county of New Haven and State of 5 Connecticut, have invented certain new and useful Improvements in Toy Submarines, of which the following is a full, clear, and exact description.

This invention relates to toy boats, and it 10 has particular reference to a toy submarine propelled by a suitable motor such as a spring motor, and capable of moving under its own power for a considerable distance and also capable of automatically discharging 15 a missile or torpedo therefrom.

One of the primary objects of the invention is to furnish an efficient toy of this general character which can be readily manipulated.

20 Another object of the invention is to provide a toy submarine with mechanism controlled by the propeller-operating spring for automatically discharging a missile or torpedo from the submarine as the energy of 25 the operating spring becomes spent.

Still another object of the invention is to provide an improved construction of hull, propelling mechanism, diving rudders and other detail features.

30 To these and other ends, the invention consists in the novel features and combinations of parts to be hereinafter described and claimed.

In the accompanying drawings,

35 Figure 1 is a side elevation of a toy submarine embodying my invention;

Fig. 2 is a longitudinal, vertical, sectional view of the same;

Fig. 3 is a bottom plan view of the upper 40 portion of the hull, the metal shell which forms the lower portion of the hull being removed;

Fig. 4 is an enlarged front end view of Fig. 1; and

45 Fig. 5 is an enlarged sectional view taken on the line 5—5 of Fig. 1, looking in the direction of the arrows.

In its general aspect, my improved toy submarine comprises a substantially cigar shaped hull, having diving rudders preferably arranged at the forward portion of the hull, a rudder at the rear for steering in a horizontal plane, and a propeller at the rear operated by a suitable spring or other motor 50 housed within the sheet metal portion of the

hull. On top of the hull is a block representing a deck, and on top of the deck are blocks representing a conning tower. In the forward end of the deck is formed a socket, in which is housed a missile or torpedo, the firing of which is automatically controlled by the spring which operates the propeller. It will be understood, however, that various modifications in these features may be adopted without departing from the scope of 60 the invention as defined in the claims.

The hull of my toy submarine preferably consists of a solid upper portion 10, preferably of wood, and having a substantially flat lower face and a rounded upper face, as 65 shown in Fig. 5, and having oppositely pointed ends, as shown in Fig. 3. The lower portion of the hull preferably has a shell-like construction 11 formed of sheet metal, the upper portion of which has the 70 configuration of the upper portion of the hull, as shown in Fig. 3, in order that the upper portion may be snugly fitted in the shell-like portion of the hull, as shown in Fig. 5, the two parts of the hull being 75 secured together by tacks or any other desired means (not shown). Upon the upper face of the solid portion of the hull 10 is mounted a relatively long wooden block 12, preferably rectangular in cross-section, which represents the deck of the submarine, and upon this deck or block 12, substantially midway between the ends of the same, are mounted blocks 13 and 14, which represent a conning tower, and mounted in the block 14 are two 80 vertical wires 15 and 16, one of which has its upper end bent toward the bow and the other of which has its upper end bent toward the stern. These wires represent the periscopes. In the forward end of the deck or 85 block 12 is formed a relatively deep socket 17, in which is mounted a helical spring 18. The function of the spring 18 is to exert pressure upon the rear end of the pointed missile or torpedo 19, in order that this torpedo may be shot out of the socket 17 when the retaining means hereinafter described releases the same.

The diving rudders 20 are mounted upon the lower portion of the hull and somewhat forward of the longitudinal center of the boat. They are preferably mounted upon a rod 21 which extends through the hollow shell of the hull and extends outwardly at each side of the same, as shown in Fig. 4. 110

The rudders are preferably formed of thin metal having laterally bent portions to form holes, through which the shaft 21 is inserted, in order to retain the rudders in place upon each side of the hull. The shaft 21 has a head 22 formed upon one end of the same, the other end of the shaft being threaded and provided with a nut 23. Washers 24 are mounted on this shaft upon each side of the hull between the same and the rudder, the arrangement being such that the rudders 20 may be clamped in any desired plane by simply tightening the nut 23 upon the shaft 21. A steering rudder 25 is mounted upon the hull underneath the same and somewhat to the rear of the longitudinal center of the same. This rudder 25 is preferably adjustably secured to the underneath portion of the hull by means of a screw 26, a washer 27 being mounted upon the screw between the hull and the rudder. This simple securing means permits the rudder to be clamped upon the hull at any desired angle to the same.

25 The spring operated propelling means is secured to and supported from the under face of the wooden block 10, which forms the upper portion of the hull. To the lower face of this member 10 is secured a substantially U-shaped frame 28, the same being preferably secured to the lower face of the member 10 by screws such as 29. This frame 28 forms a bracket for rotatably supporting the propeller operating shaft 30, upon the outer end of which is rigidly secured the screw propeller 30', and for also rotatably supporting the winding shaft 31. The forward end of the shaft 31 projects through an opening in the bow of the sheet metal portion of the hull 11. This forward end is bent to form a crank handle 32, by means of which the shaft may be rotated to wind the helical operating spring 33. This spring 33 surrounds the shaft 31 and is positioned within the frame 28. One end of this spring is anchored to a disk 34, which disk is rigidly secured to the shaft 31, and the other end of this spring is secured to the large gear wheel 36, which is loosely mounted upon the shaft 31. A washer 35 is preferably provided between the gear wheel 36 and the rear end of the frame 28. A spool or tubular member (not shown) is preferably mounted about the shaft 31 within the spring 33 and is rigidly secured to the disk 34, this spool serving to fill up the space between the shaft and the interior of the spring 33 to keep the coils of the spring in alignment. The gear wheel 36 meshes with a pinion 37 rigidly secured to the shaft 30. One face of this pinion abuts against the rear end of the frame 28 and holds the shaft 30 against longitudinal movement in one direction, and this shaft is preferably prevented from moving longitudinally in the opposite direction by a set-

up portion such as 39, formed upon the shaft. In order to provide means for preventing the shaft 31 from rotating in the reverse direction as the same is rotated to wind the spring 33, I provide a cam wheel 40, which is rigidly mounted upon this shaft and which co-operates with a pawl or detent, designated in its entirety by 41. The operation and construction of this pawl are important, as it serves a double function, as will hereinafter appear. The pawl is preferably constructed of a relatively long, narrow sheet metal strip having one end 41' secured to the under face of the member 10 by one or more screws such as 41''. The intermediate portion 41''' of this strip is then bent at right angles to the portion 41' adjacent to the ratchet wheel 40, the same being spaced a slight distance from the under face of the member 10, as shown in Fig. 2. The opposite end 41'''' of this long, narrow strip is bent at right angles to the intermediate portion and extends upwardly through a drill hole 42 extending vertically through the member 10 and into the socket 17 above mentioned. The outer end 90 of this flexible strip is positioned to engage a circumferential groove 43 formed about the rear end of the torpedo 19. The forward end of the winding shaft 32 is preferably provided with a bearing bracket 44, which is secured to the under face of the member 10 by a screw 45. In order to provide means for preventing the propeller from being rotated by its spring until it is desired to operate the same, I provide a latch member 46, 100 pivotally secured to the under face of the member 10 by a screw 47. This latch member is preferably provided with legs extending at right angles to each other, one leg 46' being positioned to be moved into and out of engagement with the gear wheel 36 to hold the same against rotation, and the other leg 46'' being positioned to project through an opening in the side of the hull, in order that the same may be manually engaged to operate the latch member. 110

The operation of my device is as follows: When it is desired to use my toy submarine, the spring 33 is placed under tension by rotating the crank handle 32. This rotates the end of the spring 33 which is attached to the disk 34 rigidly mounted upon the shaft 31, the other end of the spring being held against rotation since it is secured to the gear wheel 36, loosely mounted on its shaft, 115 which gear wheel it dogged against rotation by the latch member 46. As the shaft 31 is rotated to wind the spring, the cam wheel 40 rigidly secured to this shaft will engage the portion 41''' of the flexible strip 41, thus preventing this shaft from rotating in the reverse direction. The engagement between the ratchet wheel 40 and the co-operating pawl 41'', however, serves another important function, since the pressure exerted 125 130

upon this member 41" by the ratchet wheel 40 forces the outer end of the portion 41"" into engagement with the groove 43 formed in the rear end of the torpedo 19, so that this 5 torpedo is retained within the socket 17 against the tension of the spring 18. When my toy submarine is placed in the water preparatory to sailing the same, after the spring 33 has been placed under tension and 10 after the torpedo 19 has been placed in the socket 17 ready to be fired, the latch member 46 is disengaged from the gear wheel 36 by means of the protruding end 46", whereupon the propeller shaft 30 is rotated to operate 15 the screw propeller 30' and thereby propel the toy submarine through the water. As the spring 33 gradually unwinds, the pressure exerted upon the dogging device 41" by the cam wheel 40 will gradually decrease 20 until this pressure ceases to be sufficient to retain the outer end of the strip 41"" in engagement with the torpedo 19, whereupon the torpedo is released and is shot forward by the compressed spring 18. In other 25 words, the torpedo is retained in its socket while the torpedo boat is being propelled through the water by the screw propeller, but when the energy of the spring is spent, the strip 41 will be disengaged from the torpedo 19, due to the resiliency of this strip, 30 which tends to withdraw the outer end of the same from engagement with the torpedo, whereupon the torpedo is discharged from the torpedo boat. In Fig. 5 of the drawing, 35 I have shown the flexible strip 41 in full lines as disengaged from the torpedo, and have indicated in dotted lines the position this spring occupies when forced into engagement with the torpedo 19 by the reaction 40 of the spring 33 through the cam wheel 40.

If it is desirable to make my toy submarine submerge, all that is necessary is to tilt the diving rudders 20, so that their forward ends are directed downwardly, whereupon the toy boat will gradually submerge as forced through the water by the propeller screw, but when the energy of the driving spring is spent and the propeller ceases to 45 rotate, the buoyancy of the torpedo will then bring the same to the surface of the water.

From the above description, it will be apparent that the coöperation between the rigid disk 40 and the pawl member 41 serves 50 not only to prevent the winding shaft 31 from rotating in the reverse direction, but also provides means for releasing a torpedo 19, in order that the same will be fired from the torpedo boat when the energy of the operating spring is spent.

The exterior metal portions of the device are covered with a suitable paint to prevent rusting, and as the spring mechanism contained within the hull will become wet when 55 the toy is used, it should be well oiled, so

that in this case also there will be no rusting of metallic parts.

Various changes may be made in the details of the construction without departing from the scope of the invention. 70

What I claim is:

1. A toy submarine, having a hull, a deck upon said hull, said deck having a torpedo-receiving opening in one end thereof, a spring operated propeller for said submarine, and means controlled by the tension of said spring for releasing a torpedo from said torpedo-receiving opening, said means including a shaft for placing said spring under tension. 75

2. A toy submarine, having a spring-operated propeller, means for projecting a torpedo from said submarine, and means including a detent and coöperating cam wheel controlled by the reaction of said spring 80 for retaining said torpedo in position, said means being released automatically as the energy of said spring is spent, whereby said torpedo is automatically discharged. 85

3. In a device of the class described, a spring-operated shaft, a detent for holding an element against movement, means normally retaining said detent out of engagement with said element, a winding shaft for placing said spring under tension, and a ratchet wheel upon said shaft coöperating with said detent to prevent said shaft from unwinding, said detent being forced into operative engagement with said element by the reaction of said spring, and automatically 90 disengaged from said element as the energy of said spring is spent. 100

4. In a device of the class described, a spring-operated shaft, a detent for holding an element against movement, means normally retaining said detent out of engagement with said element, and means upon said shaft actuated by the reaction of said shaft-operating spring to retain said detent in operative engagement with said element, 105 whereby said element is automatically released as the energy of said spring is spent. 110

5. In a device of the class described, a spring-operated shaft, means including a detent and cam wheel controlled by said operating spring to hold an element against movement, said means being forced into engagement with said element when said spring is placed under tension and released from said element when the energy of said 115 spring is spent, whereby said element is automatically released as said spring unwinds. 120

6. In a toy submarine, having a hull, a deck upon said hull, said deck being provided with torpedo firing means, means for retaining a torpedo in position to be fired, power means including a rotating shaft for operating a propeller screw, a second shaft operatively connected to said power means, 125 130

and means controlled by said second shaft for automatically releasing said torpedo-retaining means.

7. In a toy submarine, having spring-operated propeller mechanism and spring means for projecting a torpedo, means for retaining a torpedo in position to be projected, said retaining means comprising a 5 detent and a cam wheel coöperating therewith, said detent being constructed to be moved into operative position by said propeller spring when the same is placed under tension and moved to inoperative position as the energy of said propeller spring is 10 spent.

8. In a toy submarine, means for projecting a torpedo therefrom, spring operated means for operating a screw propeller, a crank shaft for placing said spring under tension, means for preventing said shaft 15

from rotating in an unwinding direction, said last means being constructed to automatically release a torpedo from said projecting means as the energy of said spring is spent.

9. In a toy submarine, means for projecting a torpedo therefrom, spring operated means for operating a screw propeller, a resilient detent having a torpedo engaging portion, a spring operated screw propeller, a shaft having one end of the propeller operating spring connected thereto, and means upon said shaft for holding said detent in engagement with said torpedo, said means being constructed to automatically release said torpedo as the energy of said spring is spent.

In witness whereof I have hereunto set my hand on the 7th day of May, 1918.

ALFRED C. GILBERT.
